UNITED STATES PATENT OFFICE.

HARVEY A. MOYER AND CHARLES J. GRAF, OF SYRACUSE, NEW YORK; SAID GRAF ASSIGNOR TO SAID MOYER.

THILL-COUPING.

SPECIFICATION forming part of Letters Patent No. 591,561, dated October 12, 1897.

Application filed August 12, 1897. Serial No. 647,965. (No model.)

To all whom it may concern:

Be it known that we, HARVEY A. MOYER and CHARLES J. GRAF, of Syracuse, in the county of Onondaga, in the State of New York, 5 have invented new and useful Improvements in Thill-Couplings, of which the following, taken in connection with the accompanying drawings, is a full, clear, and exact description.

- 10 This invention relates to the class of thill-couplings which are designed to facilitate the operation of connecting and disconnecting the thills to and from the vehicle; and it has special reference to the species of couplings 15 which is provided with a fixed jaw or shackle-eye section and a movable jaw or eye-section receiving between them the coupling pin or bolt and means for locking and unlocking the movable jaw in its closed position.
- 20 The object of our invention is to provide a thill-coupling which shall be simple in construction and efficient and reliable in operation; and to that end the invention consists, essentially, of a thill-coupling comprising two 25 jaws or eye-sections grasping between them the coupling pin or bolt and separable to release the same and a spring connected to one of the parts to be coupled and reversible thereon and thereby confining and releasing the 30 coupling-pin in and from the grasp of the jaws, as hereinafter more fully described, and set forth in the claims.

In the annexed drawings, Figures 1 and 2 are side views of a thill-coupling embodying 35 our invention and showing the same in its coupled and uncoupled condition. Fig. 3 is a plan view of said coupling in the condition shown in Fig. 1. Fig. 4 is a longitudinal section on line $x-x$ in Fig. 1, and Figs. 5, 6, and 40 7 illustrate modifications of our invention.

Similar letters of reference indicate corresponding parts.

A denotes the axle, and a is the draft-bar, which is fastened to the axle by a clip b in the 45 usual manner and is formed with a forward extension terminating with a hook-shaped jaw or shackle-eye section c , formed integral therewith.

c' represents the movable jaw, which we preferably hinge to the draft-bar a back of 50 the hook c , as shown at c^2 .

t' represents the coupling-pin, which we preferably form integral with the thill-iron t and tapering from opposite ends to the center, as shown in Fig. 4 of the drawings. 55

The adjacent faces of the jaws c c' , which embrace said pin, are shaped correspondingly to wedge the pin endwise in the jaws.

To facilitate the operation of connecting and disconnecting the thills to and from the 60 vehicle by simple, inexpensive, and efficient means, we employ a spring C , which is **C**-shaped or curved, so as to have its ends pointing approximately in the same direction, and is pivotally connected at one end to one of the 65 parts to be coupled, which part is provided with the fixed jaw c , and may be either the draft-bar a , as shown in Figs. 1, 2, and 3 of the drawings, or the thill-iron t , as represented in Fig. 6 of the drawings. Said connection 70 of the spring is made by folding the end thereof around the cross-bar of a rectangular eye e , fastened either to the draft-bar a or to the thill-iron t and disposed parallel with the axle, so as to allow the spring to swing in a 75 plane at right angles to the axle.

Instead of attaching the eye e directly to the draft-bar a , as shown in Figs. 1 and 2 of the drawings, said eye may be attached to an extra bar e' , secured to the under side of the 80 draft-bar, by means of the clip b and its nuts b' , as shown in Fig. 5 of the drawings.

To the free end of the spring C is connected a link l , which is either connected to the movable jaw c' or made to extend across the top 85 of an extension of said jaw, which latter is illustrated in Figs. 6 and 7 of the drawings. We prefer, however, to connect the link l to the jaw c' , as represented in Figs. 1 and 2 of the drawings, for the purpose of causing 90 said jaw to be thrown out of its closed position automatically with the swinging of the spring C on its pivot.

The pivoted end of the spring is made to extend beyond the free end thereof for the 95 purpose of causing it to become locked in its

position when holding the jaw c' in its closed position, as shown in Fig. 1 of the drawings, and to throw said jaw out of its locked position when the spring is swung into a reversed position, as shown in Fig. 2 of the drawings.

The operation of our improved thill-coupling in connecting and disconnecting the thills to and from the vehicle is as follows, to wit: To connect the thill, the spring C is swung on its pivot to a position which causes the spring to push the jaw c' away from the stationary jaw c , as illustrated in Fig. 2 of the drawings, or to release the jaw c' from the pressure of the link l, as represented by dotted lines in Figs. 6 and 7 of the drawings, in which latter case the link l has to be thrown off from the jaw c' and said jaw to be lifted by hand to permit the coupling-pin t' to be introduced into the fixed eye-section c. After this has been effected the link l in Figs. 6 and 7 is to be placed upon the jaw c' and the spring C to be swung on its pivot into a reversed position, and in doing this the free and shorter end of the spring passes over the eye e and thereby compresses the spring and causes the same to force the jaw c' into its closed position to firmly grip the coupling-pin t', and as the free end of the spring passes beyond the eye e the spring becomes locked in the aforesaid compressed position and securely retains the jaw c' in its said closed position. By connecting the link l to the jaw c' , as shown in Figs. 1 and 2 of the drawings, the said jaw is caused to move automatically to and from its closed position by the swinging of the spring, and neither the jaw nor the link require manipulation.

It will be observed that in our improved thill-coupling the spring C is permitted to exert its elasticity throughout its entire length, and thereby the liability of breaking the spring by undue strain is in a great measure obviated, and by making said spring serve the purpose of the extra locking-lever employed in other thill-couplings we simplify the construction and reduce the cost of the manufacture of the thill-coupling.

It will also be observed that the loop formed by the C shape of the spring serves as a convenient handle by which to manipulate said spring.

What we claim as our invention is—

1. A thill-coupling comprising two jaws or eye-sections grasping between them the coupling pin or bolt and separable to release the same, and a spring connected to one of the parts to be coupled and reversible thereon and thereby confining and releasing the coupling-pin in and from the grasp of the jaws.
2. A thill-coupling comprising a fixed jaw and a movable jaw receiving between them the coupling pin or bolt, a spring pivoted at one end to one of the parts to be coupled, and a link actuated by said spring and pressing

the movable jaw onto the coupling pin or bolt 65 by the movement of the spring in one direction on its pivot.

3. A thill-coupling comprising a fixed jaw and a movable jaw receiving the coupling-pin between them, a spring pivoted at one end to 70 swing in a plane at right angles to the axle, and a link actuated by the free end of said spring and forcing the movable jaw into its closed position by the swinging of the spring in one direction.

4. The combination with a fixed jaw and a hinged jaw receiving the coupling-pin between them, a spring pivoted at one end to the member carrying the fixed jaw, and a link connected to the free end of said spring and 80 forcing the hinged jaw into its closed position by the swinging of the spring in one direction.

5. The combination with a fixed jaw and a hinged jaw receiving the coupling-pin between them, a spring pivoted at one end to the member carrying the fixed jaw, and a link connected at its opposite ends, respectively, to the free end of the spring and to the hinged jaw to move the same to and from its closed 90 position automatically with the swinging of the spring on its pivot.

6. The combination with a fixed jaw and a movable jaw receiving the coupling-pin between them, of a C-spring having one end 95 extending beyond the other end and pivoted at the longer end to the member carrying the fixed jaw, and a link connecting the shorter end of said spring to the movable jaw.

7. The combination of the draft-bar provided with a fixed hook-shaped jaw for receiving the coupling-pin, a locking-jaw hinged to said draft-bar and confining the locking-pin in the said fixed jaw, a C-spring having one end extending beyond the other and hinged 105 to the draft-bar, and a link connecting the shorter end of the spring to the hinged jaw, as set forth and shown.

8. The combination with the thill-iron and coupling-pin affixed thereto, the draft-bar 110 formed with a hook-shaped jaw for receiving said coupling-pin, a locking-jaw hinged to said draft-bar and confining the coupling-pin in said hook-shaped jaw, an eye attached transversely to the draft-bar, a C-spring 115 hinged at one end to said eye, and a link connecting the opposite end of said spring to the hinged jaw, substantially as set forth and shown.

9. In a thill-coupling having a fixed jaw 120 and a movable jaw receiving the coupling-pin between them, the combination of a C-spring pivotally connected at one of its ends to one of the parts to be coupled and a link connecting the free end of the spring to the 125 movable jaw, the swinging of the spring on its pivot in one direction forcing the movable jaw into its closed position and locking the

spring, and in swinging the spring in the opposite direction throwing the said jaw into its open position, as set forth.

10. In a thill-coupling having a fixed jaw 5 and a movable jaw receiving the coupling-pin between them, the combination of a spring having its ends pointing approximately in the same direction and one end pivotally connected to one of the parts to be coupled, and o the opposite end coupled to the movable jaw, the swinging of the spring on its pivot into a

reversed position causing the free end thereof to cross the pivoted end and force the jaw to its closed position and retain the spring in its reversed position.

In testimony whereof we have hereunto signed our names this 3d day of August, 1897.
